COMBINED ELECTRICAL FACE PLATE AND MODULAR INSERTS THEREFOR

Russell C. Edmisson, Bellflower, Calif., assignor to Sierra Electric Corporation, Gardena, Calif., a corporation of California

Filed June 22, 1966, Ser. No. 2,773

Term of patent 14 years

(Cl. D26—13)

FIG. 1.

FIG. 2.

FIG. 3.

FIG. 4.

FIG. 5.

FIG. 1 is an elevation showing in perspective a combined electrical face plate and modular inserts therefor assembly embodying my new design;

FIG. 2 is a view showing the assembly of FIG. 1 in front elevation;

FIGS. 3 and 4 are respectively side and end elevations of FIG. 2; and

FIGS. 5 and 6 are enlarged cross sections taken respectively on lines 5—5 and 6—6 of FIG. 2.

The dominant features reside in the solid line portion which is further characterized by the square module inserts contained in edge to edge relationship with the face slot.

I claim:

The ornamental design for a combined electrical face plate and modular inserts therefor, substantially as shown and described.
